ERNEST ANSLEY WATSON, OF COVENTRY, ENGLAND, ASSIGNEE TO THE M-L MAGNETO
SYNDICATE LIMITED, OF COVENTRY, ENGLAND.

CONDENSER FOR IGNITION-MAGNETOS.

1,307,716.

Specification of Letters Patent. Patented June 24, 1919.

Application filed June 5, 1918. Serial No. 238,302.

To all whom it may concern:

Be it known that I, ERNEST ANSLEY WATSON, residing at Victoria Works, West Orchard, Coventry, in the county of Warwick, England, subject of the King of Great Britain and Ireland, have invented certain new and useful Improvements Relating to Condensers for Ignition-Magneton, of which the following is a specification.

This invention has for its object to provide a condenser of improved construction for ignition magnetos of the rotary wound armature type. With the ordinary construction difficulty is sometimes found in effecting a secure mounting of the condenser in the usual condenser box at one end of the armature, and particularly when the armature is run at high speeds or is subject to vibration. By this invention a rigid and durable mounting is obtained in a very simple manner.

The invention comprises the arrangement of the alternate conducting sheets to project beyond the insulating sheets at a pair of edges which are at right angles (or alternatively the alternate conducting sheets are disposed at right angles to the other sheets with both ends projecting beyond the insulating strips), and the employment of metal clips at a pair of opposite edges of the condenser which are adapted to be pressed tightly into contact with a pair of parallel sides of the condenser box, sufficient clearance being provided in the box to accommodate a band or its equivalent embracing the other pair of edges of the condenser and having the insulated terminal of the contact breaker attached thereto.

Referring to the accompanying sheet of explanatory drawings:—

Figure 1 is a rear elevation of a condenser box fitted with a condenser constructed in accordance with this invention.

Figs. 2 and 3 are respectively cross sections on the lines 1, 2, and 3, 4. (Fig. 1).

In carrying the invention into effect as shown, the layers or sheets of tinfoil are interposed with layers or sheets of mica or paper, the alternate metal sheets being arranged at right angles to the others and with both ends projecting beyond the mica. In Fig. 1 the horizontal pair of dotted lines *a* indicate diagrammatically the posi-

tion of one set of metal sheets and the vertical dotted lines *b* that of the other sheets. 55

In other words one metal sheet projects at both ends beyond one opposite pair of edges of the mica, while the next projects at both ends beyond the other opposite pair of edges of the mica. This order is then 60 continued so that one set of metal sheets lie in one direction and the alternate set in the direction at right angles. It will be

understood that the two sets of metal sheets are insulated by the mica. It is not essential for each sheet to project at both ends beyond the mica, projection at one end being sufficient, although it is usually more convenient to provide for projection at both ends. Preferably the mica sheets *c* are of 70

square or rectangular form. The metal sheets projecting from the same side of the mica strips are folded into contact, and along each of a pair of opposite edges a metal clip *d* is slipped over the pile to hold 75

the parts together. Around the other pair of edges a metal band is secured. This band consists of a main part *e* recessed to take the condenser and formed on its rear side with an internally screwed boss *f* or the like for 80

the connection thereto of the usual central screw *g* of the contact breaker. The band is completed by a front piece *h* secured to the part *e* by screws *i*. Between the parts *e* and *h* is clamped a metal strip *j* on which 85

are formed ear pieces *k* for attachment

thereto of the armature wires. By means of the band the condenser components are secured tightly together.

The condenser box *l* is formed internally 90 with a pair of parallel side cheeks *m* between which the clips *d* above mentioned can be tightly inserted. Adjacent to the other edges of the condenser around which the metal band is placed sufficient clear space is 95

provided in the box to avoid metallic connection. Protection against metallic contact of the band with the box is made in any convenient manner such as by an insulating bush *n* placed over the boss *f* and a 100 sheet of insulation *o* fitted against the base of the box. A lug *p* is formed on either or both of the clips *d* and a screw *q* is inserted through the same into the condenser box for completing the security of the condenser. 105

By constructing and arranging the condenser as above described a rigid and solid mounting of the condenser is obtained which effectively avoids the occurrence of trouble 5 due to high speeds or vibration.

In a modification the alternate conducting layers may each be formed from a single strip which is folded in opposite directions upon itself. Likewise the insulating layers 10 may be formed from a single strip. If desired only one end of each layer may be arranged to project beyond the insulating layers in the construction first described.

Having thus described my invention what 15 I claim as new and desire to secure by Letters Patent is:—

1. In condensers for ignition magnetos, the combination comprising alternate conducting and insulating sheets, the alternate 20 conducting sheets projecting beyond the conducting sheets at edges which are at right angles, metal clips embracing a pair of opposite edges of the conducting and insulating sheets, a metal box formed with a pair 25 of parallel sides between which said clips are tightly fitted, a metal band embracing the other pair of edges of said sheets, and insulating material between said band and the box, substantially as described.

2. In condensers for ignition magnetos, the combination comprising alternate conducting and insulating sheets, the alternate 30 conducting sheets projecting beyond the conducting sheets at edges which are at right angles, metal clips embracing a pair of op-

posite edges of the conducting and insulating sheets, a metal box formed with a pair of parallel sides between which said clips are tightly fitted, a metal band embracing the other pair of edges of said sheets, said 40 band consisting of a recessed main part which receives the condenser sheets, a boss formed on the rear side of said part, a front detachable part, screws for securing the front part to the main part, and insulating 45 material between the said band and the box, substantially as described.

3. In condensers for ignition magnetos, the combination comprising alternate conducting and insulating sheets, the alternate 50 conducting sheets projecting beyond the conducting sheets at edges which are at right angles, metal clips embracing a pair of opposite edges of the conducting and insulating sheets, a metal box formed with a pair 55 of parallel sides between which said clips are tightly fitted, a metal band embracing the other pair of edges of said sheets, said band consisting of a recessed main part which receives the condenser sheets, a boss 60 formed on the rear side of the said part, a front detachable part, screws for securing the front part to the main part, a metal terminal strip clamped between the main and detachable parts of said band, and insulating 65 material between the said band and the box, substantially as described.

In testimony whereof I have signed my name to this specification.

ERNEST ANSLEY WATSON.
